UNITED STATES PATENT OFFICE.

JENS KNUDSON, OF DES MOINES, IOWA.

MITER-BOX.

No. 877,651.

Specification of Letters Patent.

Patented Jan. 28, 1908.

Application filed May 13, 1907. Serial No. 373,320.

To all whom it may concern:

Be it known that I, JENS KNUDSON, a citizen of the United States of America, and resident of Des Moines, Polk county, Iowa, have 5 invented a new and useful Miter-Box, of which the following is a specification.

The object of this invention is to provide improved construction for miter boxes.

A further object of this invention is to provide 10 means for constructing a miter box open at the front for the placing and removal of material beneath the saw.

My invention consists in the construction, arrangement and combination of elements 15 hereinafter set forth, pointed out in my claims and illustrated by the accompanying drawing, in which—

Figure 1 is a plan of the complete miter box in position for making a bevel cut. Fig. 20 2 is an end elevation of the miter box in position to make a square cut. Fig. 3 is a front elevation of the same, the saw removed, the dotted lines indicating positions assumed by 25 parts in making under-cuts and miter-cuts. Fig. 4 is a detail section on the indicated line 4—4 of Fig. 3. Fig. 5 is a detail section illustrating certain structural elements. Fig. 6 is a detail section on the indicated line 6—6 30 of Fig. 1. Fig. 7 is a detail section on the indicated line 7—7 of Fig. 1.

In the construction of the miter box as shown, the numeral 10 designates a bed or base fixed to and carried by legs 11, 12. The legs 11, 12 are arched intermediate of their 35 ends and are adapted to rest upon or be fixed to a suitable support (not shown) such as a work bench. A semicircular plate 13 is fixed to the lower face of the bed or base 10 intermediate of the legs and the plane diametrical margin of said plate is flush with the rear 40 margin of the base while the convex margin of the plate projects forward from the front margin of the base. An ear 14 projects rearwardly from the center of the rear margin of 45 the plate 13 and a lever 15 is fulcrumed on said ear by a bolt 16. The lever 15 extends across the plate 13 and projects at each end therefrom. A cap screw 17 is seated in the forward portion of the lever 15 and the head 50 thereof overlaps the curved forward margin of the plate 13 and is adapted to slide thereon. An adjusting screw 18 is seated in the lever 15 beneath and adapted for contact by the head of the cap screw 17, and said adjusting 55 screw determines the degree of seating of the cap screw and adjusts the tension with which

the lever is held to the plate 13. A latch 19 is fulcrumed at its rear end on the lever 15 and extends forwardly beneath and nearly to the front end of said lever. Screws or posts 60 20, 21 are seated in the lever 15 and extend downward on opposite sides of the latch 19. A bar washer 22 is mounted loosely on the screws 20, 21 and crosses beneath the latch 19. Expansive coil springs 23, 24 are mounted on 65 the screws 20, 21 between and impinging the heads of the screws and the bar washer 22. It is the function of the springs 23, 24 to hold the latch 19 yieldingly against the bottom of the lever 15. A pin 25 is mounted pivotally 70 in the latch 19 and extends vertically through an aperture in the lever 15 and through one or another of holes 26 in the plate 13. It is the function of the pin 25 to lock the lever in any desired angle relative to the plate 13. A 75 headed pin 27 is fixed in the outer end portion of the latch 19 and extends loosely through an aperture in the outer end portion of the lever 15. It is the function of the headed pin 27 to receive thumb pressure of the operator and depress the latch 19 sufficiently to withdraw the pin 25 from engagement with the plate 13 and permit an angular adjustment of the lever 15 relative to said plate. That portion of the lever 15 at the rear of the 80 bolt 16 is formed as a journal and a sleeve 28 is mounted loosely thereon. Holes 29 are formed in the sleeve 28 and its journal (Figs. 2 and 6) and a key 30 is mounted removably, replaceably and interchangeably in said holes 90 to determine circumferential adjustment of the sleeve on the journal. Guides 31, 32, arranged in pairs, are fixed at their lower ends to and rise from the ends of the sleeve 28. The guides 31, 32 are spaced apart in 95 the pairs and are connected rigidly by a cross-bar 33 at their upper ends.

A saw-carrier is mounted slidably in the guides 31, 32 and a saw 43 may be mounted slidably in the carrier. The saw-carrier is 100 constructed as follows: Plates 34, 35 are arranged parallel with each other between and in contact with the inner faces of the guides 31, 32, and are connected at their upper and lower ends by cleats 36, 37. Lugs 38 are 105 fixed to the outer faces of the plates 34, 35 and slidably engage the adjacent margins of the guides 31, 32 and steady the carrier in vertical movement in the guides. Saw-guides 39, 40 are mounted horizontally 110 transversely of the inner faces of the plates 34, 35 and the end portions of said guides

project from the front and rear margins of the plates and are slightly closer together than the centers thereof. The saw-guides 39, 40 are arranged in pairs and the pair 40 5 may be adjusted to greater altitude by removing the screws 41 from the holes in which they are shown in the plates 34, 35 (Fig. 2) and raising the guides and replacing the screws in the holes 42 in said plates. Thus 10 is provision made for raising the guides to compensate for wear of the saw 43. The guides 39 support and receive sliding engagement of the back 44 of the saw and prevent downward movement of the saw independent 15 of the carrier. The guides 39, 40 on opposite sides of the saw maintain the blade parallel with the plates 34, 35 of the carrier. A stop 45 is mounted adjustably on one of the guides 31 and is adapted to be engaged 20 by and limit downward movement of the saw-carrier. A detent 46 is pivoted on the cross-bar 33 and is held yieldingly in one direction by a spring 47. A stud 48 on the cleat 36 is adapted to be engaged by the detent 46 to hold the carrier and saw in the uppermost limit of movement thereof, when 25 the saw is not in use. The detent may be moved manually to release the stud 48 and permit the carrier and saw to descend for the use 30 of the saw as shown in Fig. 2. The sleeve 28 is further connected to its journal by a cap screw 49 seated in the rear end of said journal. Back-plates 50, 51 are provided, of like construction, each plate having 35 one straight end and one bevel end. The straight ends of the plates 50, 51 are beveled back as shown in Fig. 1. The back plates 50, 51 are secured to the base or bed 10 by cap screws 52 mounted through notches in 40 the lower margins of the plates and seated in the base. In the use of the miter box in cutting at right or acute angles with the saw and its carrier and guides upright, the back plates 50, 51 are positioned as shown with 45 their straight edges near each other and spaced apart for the passage of the saw between them. When miter or under-cuts are to be made, the screws 52 are loosened and one or the other or both of the back plates 50 are removed and interchanged or reversed 50 and replaced and tightened by the screws 52 with the inclined ends of the plate or plates toward the center, as shown by dotted lines in Fig. 3. Then the saw, carrier, and guides 55 may be tilted in either direction to an angle of 45°, by first removing the key 30 from the sleeve 28 and its journal and replacing said key in the new position to hold the sleeve to the journal.

60 Work-holders are provided and are constructed as follows: A tubular screw 53 (Fig. 5) is seated in a hole in the base 10 adjacent the inner end of either of the back plates 50, 51 and a pointed pin 54 is screwed 65 through said tubular screw. The pin 54 is

first adjusted in the screw 53 and then the latter is seated in the base 10 in such manner that the point of the pin extends above the face of the base and can engage a piece of work on said base and prevent slipping 70 thereof.

Work-clamps are provided and are constructed as follows: A tubular cylindrical block 55 is formed with a notch adapted to receive the upper margin of one of the back-plates 50, 51 and a set screw 56 is screwed into the bore of said block from the rear and impinges the back plate. A clamp screw 57 is mounted vertically through the forward portion of the block 55 and is threaded 75 thereto. The clamp screw 57 may be turned manually and the lower end of said screw is provided with a loose bushing 58 adapted to engage and hold a piece of work 59 to the base 10. A groove 60 is formed in and longitudinally of the lower face of the base 10 adjacent the back-plates 50, 51 and a rod 61 may be mounted in said groove by longitudinal movement from either end and be locked 80 therein by engagement of a set screw 62 in either of the legs 11, 12. A head 63 is mounted removably and replaceably on the outer end of the rod 61 and is adapted to be engaged by and stop the outer end of the piece of work 59. This head is employed 85 only when the work extends beyond the end of the base 10. When short pieces of work are being cut from a stick, the head 63 is removed from the rod and a return-arm 64 is attached to the outer end of the rod by an 90 elbow 64a and returns over the table or base 10 (Fig. 7). A head 65 is mounted or formed on the inner end of the return-arm and engages the end of the stick from which short pieces are being cut. Through longitudinal 95 adjustment of the rod 61 any desired length of material may be gauged relative to the plane of cutting by the saw 43.

Other work holders may be provided as follows: Transverse dovetail grooves 66, 67 may be formed in the base 10 and open to the top thereof. Blocks 68 are fitted to and arranged to slide in the grooves 66, 67 and screws 69 and threaded in and extend through said blocks. The screws and blocks are adjusted so that the forward margin of the work is engaged by the screws, and then the screws are advanced slightly and engage the bottoms of the grooves 66, 67 and lift the blocks into rigid engagement with the inclined upper walls of the grooves.

I claim as my invention—

1. A miter box, comprising a base, a lever fulcrumed for oscillation on said base, means for latching said lever to said base, a guide frame mounted for rotary adjustment on said lever and located wholly at the rear of said base, a saw-carrier slidably mounted in said guide frame, and means for locking said saw-carrier in said guide frame.

2. A miter box, comprising a base, a lever fulcrumed for oscillation on said base, means for latching said lever to said base, a guide frame mounted for rotary adjustment on said lever and located wholly at the rear of said base, a saw-carrier slidably mounted on said guide frame, means for locking said saw-carrier in said guide frame, and horizontal saw-guides in said saw-carrier.
3. A miter box, comprising a base, legs carrying said base, a lever fulcrumed for oscillation on said base, a semicircular plate projecting forward from said base, a latch connecting said lever and plate, a sleeve mounted for rotary adjustment on the rear end of said lever, yokes fixed to and rising from said sleeve, plates mounted for vertical adjustment in said yokes and located wholly at the rear of said base, means for locking said plates in said yokes, and saw-guides between said plates.
4. A miter box, comprising a base, legs carrying said base, screws seated in and projecting rearward from said base, back plates formed with marginal notches embracing said screws, said back plates each formed with a square end and a beveled end adapted to be removed and reversed and replaced relative to said screws, a lever fulcrumed for oscillation on said base, a guide frame mounted for rotary adjustment on the rear end of said lever and wholly at the rear of said base, a saw-carrier slidably mounted on said guide frame, means for locking said saw-carrier in said guide frame, and horizontal saw guides in said saw-carrier.
5. A miter box, comprising a base, legs supporting the base, a semi-circular plate mounted beneath said base and apertured in its forward curved margin, a lever fulcrumed on said plate, a latch on said lever, a pin on said latch engaging in one or another of the apertures in said plate, said latch spring-held in one direction and adapted for manual actuation in the opposite direction, a sleeve mounted for rotary adjustment on the rear end of said lever, yokes fixed to and rising from said sleeve, plates mounted slidably between said yokes, means for latching said plates in their uppermost position, and horizontal saw guides between and carried by said plates.
6. In a miter box, a base, screws mounted in and projecting rearward from said base, back plates formed with notches in their lower margins embracing said screws, each of said back plates formed with a square end and a beveled end and adapted to be removed, reversed and replaced relative to said screws, a block formed with a transverse
- groove in its lower face adapted to removably embrace and engage either margin of either back plate, a set screw mounted longitudinally of said block and intersecting the groove therein and adapted to engage the back plate, and a clamp-screw extending through said block in front of and parallel with the back plate.
7. In a miter box, a base, screws seated in said base, and back plates formed with marginal notches embracing said screws, said back plates each formed with a square end and a beveled end and adapted to be removed and replaced and reversed relative to said screws.
8. In a miter box, a base screws seated in and projecting horizontally from said base and back plates formed with marginal notches removably and replaceably mounted on said screws, said back plates each formed with one straight end and one inclined end, thus adapting said plates for adjustment in reversed positions relative to the screws.
9. In a miter box, a lever mounted for oscillation, a guide frame mounted for rotary adjustment on said lever, a saw-carrier slidably mounted in said guide frame, a detent on said frame and a stud on said carrier adapted to be engaged by said detent.
10. In a miter box, a journal, a sleeve loosely mounted thereon, said sleeve and journal formed with registering apertures, a key in said apertures, a guide frame fixed to said sleeve, a saw-carrier slidably mounted in said frame, and means for latching said carrier to said frame.
11. In a miter box, a lever, a sleeve mounted for rotary adjustment on said lever, yokes embracing and fixed to said sleeve, plates mounted between the arms of said yokes and means for adjusting said plates vertically in said yokes.
12. In a miter box, a lever, a sleeve mounted for rotary adjustment on said lever, yokes embracing and fixed to said sleeve, plates slidably mounted between the arms of said yokes, guides mounted transversely of and between said plates, and means for limiting vertical movement of said plates and guides.
13. In a miter box, a base, tubular screws mounted in said base, and pointed pins screwed through the bores of said tubular screws.
